(57) **CLAIM**

The ornamental design for a socket rails and tray, as shown and described.

DESCRIPTION

FIG. 1 is top perspective view of a socket rails and tray, showing my new design;
FIG. 2 is a bottom plan view thereof;
FIG. 3 is a top plan view thereof;
FIG. 4 is a left side elevational view thereof;
FIG. 5 is a right side elevational view thereof;
FIG. 6 is a front elevational view thereof; and,
FIG. 7 is a rear elevational view thereof.
The broken line indicate unclaimed portions and form no part of the claimed design.
